UNITED STATES PATENT OFFICE.

ARTHUR E. NEWMAN, OF SHEGUINDAH, ONTARIO, CANADA.

SWITCH.

1,150,698.

Specification of Letters Patent. Patented Aug. 17, 1915.

Application filed November 11, 1913. Serial No. 800,392.

To all whom it may concern:

Be it known that I, ARTHUR E. NEWMAN, a citizen of Canada, residing at Sheguindah, in the Province of Ontario and Dominion of Canada, have invented new and useful Improvements in Switches, of which the following is a specification.

This invention relates to switches and more particularly to a switch for controlling the multi-circuit of an electrically operated shuttle.

The primary object of the invention is the provision of a structure wherein a series of magnets that control the travel of the shuttle may be energized successively in one direction and reversed and successively energized in the opposite direction.

Another object of the invention is the provision of a switch whereby through the oscillatory motion of a rack bar the magnets will be successively energized in one direction and then successively energized in the opposite direction.

With the above and other objects in view, the invention consists in the construction, combination and arrangement of parts hereinafter set forth in and falling within the scope of the claim.

In the accompanying drawings, Figure 1 is a transverse section through a lay or batten showing one of the magnets in place. Fig. 2 is a sectional view through the switch. Fig. 3 is a detail view showing the rack bar coöperating with the gear. Fig. 4 is a side elevation of the commutator. Fig. 5 is a detail enlarged section through the commutator. Fig. 6 is a plan view of one of the commutator sections.

Referring now to the accompanying drawings in detail, A designates an appropriate form of lay or batten for looms, such lay comprising in the present instance, a horizontal plate 1 provided with depending posts 2 appropriately spaced apart and having the lower ends thereof pivoted upon alining pivot pins 3 carried by suitable bearings 4. Extending upwardly from one longitudinal edge of the plate 1 is a vertical flange 5 and secured to the upper edge of such flange and surmounting the plate 1 in parallelism therewith is a strip of metal 6 preferably composed of brass. The lay is equipped with a suitable form of reed 7 through which the warp threads pass, as usual, and serves the usual function of beating the rilling threads into the fabric as the lay oscillates or swings

back and forth. The shed is controlled by heddles operating by any approved mechanism.

Secured to the upper surface of the plate 1 between the latter and the brass strip 6 is a series of electric magnets 10 having the poles thereof in contact with the under surface of the brass strip so that upon the successive energization of the magnets, the shuttle will traverse its path of travel.

The magnets 10 are designed to be energized successively or one after the other so that the shuttle will be carried from one end of the lay to the other and upon the shuttle reaching the limit of its travel in one direction, the magnets are energized in the reverse order so that the shuttle is carried back to the initial end of the lay. For this purpose I employ a commutator comprising, in the present instance, a disk 12 fast upon a horizontal stationary shaft 13 having one end journaled in one of the bearings 4 and the opposite end journaled in a bearing 14 alining with the respective bearing 4, the shaft 13 being coaxial with the adjacent pivot pin 3. Embedded in one face of the disk 12 is a series of bars 15 extending radially of the disk and each tapering from its outer end toward the center of the disk. These bars are embedded in the face of the disk and insulated from one another and from the disk as at 16, while the inner ends thereof are formed with openings 17 alining with openings in the disk to receive pins 18 having the outer ends thereof equipped with binding nuts 19.

Loosely encircling the shaft 13 adjacent to the face of the disk carrying the commutator bars is a sleeve 20 carrying, adjacent to the disk a radially extending arm 21 equipped at its outer end with a brush 22 adapted to wipe over the bars 15. The opposite end of the sleeve 20 is equipped with a gear pinion 23 with which meshes a rack bar 24 adapted to be reciprocated in some suitable manner so that the pinion 23 and the sleeve 20 will be oscillated whereby the brush 22 will be moved back and forth over the commutator bars. Leading from one side of a suitable source of electrical energy is a power wire 25 electrically connected with the sleeve 20. In the present instance, this connection is effected through the medium of a fluid switch comprising a cup 26 containing a quantity of mercury 27, and a switch arm 28 suspended from a ring 29 loosely surrounding the sleeve, the lower end

of the switch arm being immersed in the mercury 27 in the cup. Connected to each commutator bar 15 through the medium of the binding nuts 19 and the pins 18 is a wire 30 having the free end thereof tapped onto one terminal of one of the magnets of the series 10 and the free terminals of the magnets are tapped onto a common return wire 31 leading back to the other side of the 10 source of energy and forming with the wire 25 and the wires 30 the power circuit for the series of magnets 10.

From the foregoing description taken in connection with the accompanying drawings, the construction, mode of operation and manner of employing my invention will be readily apparent. In practice, assuming the rack bar to be reciprocating and the sleeve 20 oscillating about the shaft 13, it 15 will be seen that the commutator brush 13 will move back and forth over the bars 15. As the brush wipes over the commutator bars when moving in one direction the magnets of the series 10 are energized successively or one after the other and act upon the foremost armature on the shuttle to carry the latter across the lay. Upon the direction of movement of the brush being reversed, the magnets are energized in the 20 inverse order and the other armature of the shuttle acted upon to carry the latter across the lay to its original or initial position.

While I have herein shown and described one preferred form of my invention by way of illustration, I wish it to be understood 35 that I do not limit or confine myself to the precise details of construction herein described and delineated, as modification and variation may be made within the scope of the claim without departing from the spirit 40 of the invention.

I claim:

A multi-circuit closer comprising a shaft, a disk rigidly secured to said shaft and having commutator bars embedded therein, a 45 sleeve loosely mounted on said shaft and having one end thereof shaped to form an arm, a gear formed integral with the remaining end of said sleeve, a brush carried by the outer end of the arm formed on the 50 sleeve and adapted to slide on the bars in the disk, a cup having a quantity of mercury forming a circuit terminal, a switch arm having one of its extremities encircling the sleeve, the other extremity within the 55 body of mercury, and a rack bar co-acting with said gear for giving to the said sleeve an oscillatory movement.

In testimony whereof I affix my signature in presence of two witnesses.

ARTHUR E. NEWMAN.
